(57) **CLAIM**

The ornamental design for a folding chair, as shown and described.

DESCRIPTION

FIG. 1 is a perspective view of a folding chair showing my new design.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof.

FIG. 8 is a perspective view of the folding chair of FIG. 1 shown in a folded condition; and,

FIG. 9 is a perspective view of the folding chair of FIG. 1 shown supporting a seat cushion.

The portions of the drawings appearing in broken line are for environment only and do not form a part of the design.

1 Claim, 6 Drawing Sheets
